DRY-CELL BATTERY.

Application filed March 2, 1920. Serial No. 362,655.

To all whom it may concern:

Be it known that we, HARRY M. KORETZKY and BORIS H. TEITELBAUM, citizens of the United States, and residents of the city of 5 New York, borough of Manhattan, in the county and State of New York, have invented a new and Improved Dry-Cell Battery, of which the following is a full, clear, and exact description.

10 This invention relates to dry cell batteries in which the active agents are kept separated or spaced preliminary to the time the battery is to be put into use so as to prevent any possible deterioration of the elements.

15 In this present improvement one of our objects is to provide two distinct parts for each battery which are preferably kept entirely separated preliminary to the operation of the battery, the parts however being 20 adapted to be easily assembled when and only when the battery is to be put into use.

With the foregoing and other objects in view the invention consists in the arrangement and combination of parts hereinafter 25 described and claimed, and while the invention is not restricted to the exact details of construction disclosed or suggested herein, still for the purpose of illustrating a practical embodiment thereof reference 30 is had to the accompanying drawings, in which like reference characters designate the same parts in the several views, and in which—

Figure 1 is a vertical sectional view of 35 the cup or shell portion of one form of our present improvement.

Fig. 2 is a vertical sectional view of a separate receptacle in which the depolarizing member is placed or carried, the container being adapted to be discarded when 40 the battery is put into use.

Fig. 3 is a view showing the resulting assembly of the parts shown in Figs. 1 and 2.

45 Fig. 4 is a vertical sectional view of a unitary battery complete but for the introduction of a suitable liquid or other electrolyte.

Referring now more specifically to the 50 drawings we show in Fig. 1 a cup 10 of zinc, or its equivalent, having a closed bottom and of any suitable length. This cup is ordinarily of cylindrical form but as to the form in cross section we do not 55 desire to be unnecessarily limited. With-

in the bottom of the cup is a supply of electrolyte 11 normally held in place by means of a sealing member 12 of paraffin, or the like of a nature adapted to be easily ruptured or broken by force. 60

The zinc cup 10 for practical purposes is preferably surrounded by means of a tube 13 of some suitable paper or other non-metallic material.

Within the upper or open end of the 65 cup 10 is removably fitted a closure member or stopper 14 which may be of rubber, cork, or any other suitable analogous material. This is provided with a central hole 15 sealed while in idle condition by 70 means of a paper or other seal 16.

As indicated in Fig. 2 the depolarizing member 17 in which is fitted a carbon stick 18, or its equivalent, is normally shipped or handled in a cheap paper or other cheap 75 discardable container 19, having a cap of the same material. With the depolarizing member and conductor housed as indicated the parts may be handled without any possible danger of deterioration of the active 80 elements. They may be handled or wrapped separate, or they may be wrapped together in the condition indicated without danger.

When the battery is to be used the container 19 is opened and destroyed or discarded and the depolarizing member 17 is projected into the cup 10 after the stopper 14 is removed therefrom, and after the depolarizing member is forced into the electrolyte as shown in Fig. 3 the stopper 90 14 is forced over the carbon 18 and contact cap 21, serving at the same time to seal the open end of the cup making the battery complete and active. 85

In Fig. 4 the depolarizing member 17 95 is fitted more or less permanently in the stopper 14 and these parts are fitted into the cup 10, but without an electrolyte. The battery as shown in Fig. 4 may be regarded as complete as a commercial unit, but when 100 it is to be used the stopper is removed from the upper end of the cup so as to introduce any suitable fluid to act as an electrolyte, such fluid being furnished by the dealer in any suitable separate container. 105

We claim:

1. A dry cell battery comprising two initially separate parts, one part consisting of a metallic cup carrying within it an 110

electrolyte, said cup having therein a sealed compartment for housing the electrolyte, said compartment being formed partially of walls of the cup and partially of an 5 impermanently positioned wall in the cup, and the other part including a depolarizing member having a carbon stick projecting therefrom, the complete battery being formed by plunging the depolarizing member 10 into the cup containing the electrolyte after destruction or removal of said impermanently positioned wall.

2. A dry cell battery comprising two initially separate parts, one part consisting 15 of a metallic cup carrying within it an electrolyte, said cup having therein a sealed

compartment for housing the electrolyte, said compartment being formed partially of walls of the cup and partially of an impermanently positioned wall in the cup, and 20 the other part including a depolarizing member having a carbon stick projecting therefrom, and a stopper through which said carbon stick is adapted to extend, the complete battery being formed by plunging the depolarizing member into the cup containing the electrolyte after destruction or removal of said impermanently positioned wall. 25

HARRY M. KORETZKY.
BORIS H. TEITELBAUM.
